E. C. LONG.
CAR TRUCK FRAME.
APPLICATION FILED MAY 2, 1918.

1,274,296.

Patented July 30, 1918.

UNITED STATES PATENT OFFICE.

EDWARD C. LONG, OF WESTMONT BOROUGH, PENNSYLVANIA.

CAR-TRUCK FRAME.

1,274,296.

Specification of Letters Patent.

Patented July 30, 1918.

Application filed May 2, 1918. Serial No. 232,024.

To all whom it may concern:

Be it known that I, EDWARD C. LONG, a citizen of the United States, and a resident of Westmont borough, county of Cambria, 5 and State of Pennsylvania, (whose post-office address is Johnstown, Pennsylvania,) have invented certain new and useful Improvements in Car-Truck Frames; and I do hereby declare the following to be a full, 10 clear, and exact description of the invention, such as will enable others skilled in the art to which it appertains to make and use the same.

My invention relates to car trucks and 15 particularly to the arrangement and construction of the side frames of those adapted for use with freight or passenger cars.

My car truck frame consists essentially of a truss-like structure having an upper member 20 corresponding with the upper chord and a lower member corresponding with the lower chord; diagonal members uniting the two and acting principally in tension; end members adapted to serve as pedestals or 25 supports on the journal boxes and upright members serving also as column guides. My car truck frame is also provided with a spring-seat, bolster guides, pedestal tie-bars and connections for the same.

30 One of the essential features of my construction resides in the fact that the main structural member of my car truck frame is composed of one piece of rolled steel which may first be formed of section some- 35 what resembling an I-beam but with the flanges on one side preferably shorter than those on the other. The intermediate portion of said I-beam is split or divided through the web longitudinally thereof and 40 substantially at right angles to the flanges, thus making two channel sections. The intermediate portions are then spread or spaced apart, truck column guides applied and secured by riveting or bolting, thus 45 forming the truss structure of my frame. This construction makes a frame, the principal portions of which are formed entirely 50 of one piece of metal, integral at their end portions, split and separated at their intermediate portions to provide a greater depth and also room for the reception of the springs and the end of the body bolster resting thereon.

Having thus given a general description 55 of my invention, I will now, in order to make the same more clear, refer to the one sheet of

drawings accompanying and forming part of this specification, and in which like figures refer to like parts:—

Figure 1 is a side elevation of a car truck 60 frame embodying my invention;

Fig. 2 is a top plan view;

Fig. 3 is a side elevation of the bar from which the main members are formed;

Fig. 4 is a vertical transverse sectional 65 elevation taken on the line IV—IV of Fig. 1;

Fig. 5 is a vertical transverse section of the bar taken on the line V—V of Fig. 3;

Fig. 6 is an end elevation of my improved truck side frame; 70

Fig. 7 is a cross section of a modified form of bar which I may use;

Fig. 8 is a top plan view of one of the truck columns; and

Fig. 9 is a transverse section of the lower 75 arch bar taken on the line IX—IX of Fig. 1.

Referring now to the characters of reference on the drawings:—

1 is the car truck frame as a whole, 2 is the space or opening between the upper and 80 lower members, 3 are the flanges of the upper arch bar, 4 is the web thereof, 5 are the beveled or cut-away ends of the flanges 3, this formation being for the sake of lightness and appearance, 6 is the web portion of 85 the lower arch bar, 7 are the downwardly projecting flanges thereof, 8 are the inclined members, 9 being the bent portions of the flanges thereof, as illustrated. 10 are the end portions or journal box bearings which 90 are integral, 11 are holes through the thick web of the end portions adapted to receive the usual journal box bolts, 12 are the truck columns, shown as of channel or trough section with the ends of the webs cut away to 95 adapt them to fit around the upper and lower arch bars, as shown. 13 are the column guides which are composed of flat plates riveted by countersunk rivets to the webs of the truck columns 12, 14 is a plate 100 bent into trough shape to form a spring seat and riveted to the lower arch bar and the column guides as shown, this being provided with a filler plate 15 secured thereto to form a portion of the spring seat, the 105 spring plank being composed of angles 16 riveted to the frame as shown. 17 are the pedestal tie brackets to which the pedestal tie bars 18 are secured. 19 indicates the cross section of a rolled steel bar of approxi- 110 mately I-beam shape, from which the main members are formed, as above described,

2
this bar, in forming, being split longitudinally of the web at its intermediate portions, leaving the ends integral and the split channel-shaped portions spread apart to the 5 form illustrated. As illustrated in Fig. 7 20 is a modified form of bar or beam from which my main members may be formed, this being provided with grooves 21 to facilitate the splitting thereof. This bar may be 10 split by sawing, slotting, shearing or any other way that may be suitable and the portions may preferably be heated before being shaped into their final form.

It should further be noted that the 15 portions 9 and 10 are formed integrally by bending the edges of the flanges inwardly, thereby forming a tapering section of the inclined member 8 and forming substantial bearing surfaces 10, as illustrated, which 20 comprise the seats which are adapted to rest upon the journal boxes, not shown.

By reason of my construction and arrangement, a very simple frame is provided, the main members of which are formed of 25 one piece and, including the column guides, the entire main trussed frame is composed of only three pieces.

Although I have described and illustrated my invention in considerable detail, I do not 30 wish to be limited to the exact and specific details thereof as shown and described, but may use such modifications in, substitutions for, or equivalents thereof, as are embraced within the scope of my invention, or as 35 pointed out in the claims.

Having thus described my invention, what I claim and desire to secure by Letters Patent is:—

1. In a truck frame, upper and lower arch 40 bars of channel section with their flanges projecting outwardly and the webs integrally united at their end portions.

2. In a truck frame, upper and lower arch 45 bars of channel section with their flanges projecting outwardly, inclined members connecting the same, the webs being integrally united at their end portions.

3. A truck frame comprising an upper arch bar of channel section with flanges projecting upwardly, a lower arch bar of channel section with flanges projecting downwardly, inclined members connecting the same, integrally united at their end portions.

55 4. In a truck frame, upper and lower arch bars of channel section, the webs of which are integral at their end portions, the flanges of the end portions being turned inwardly forming bearings.

60 5. A truck frame comprising upper and lower arch bars and inclined members con-

necting the same, all of channel section, the webs of which are integral at their end portions, the lower portions of the flanges of the end and side members being turned inwardly. 65

6. A truck frame comprising upper and lower arch bars of channel section with their flanges projecting upwardly and downwardly respectively and integrally united at their end portions, column guides formed of channel or trough section with the end portions of their webs cut away, adapted to fit against said upper and lower arch bars, the flanges of said column guides being secured 75 to the flanges of the arch bars.

7. In a truck frame provided with upper and lower arch bars, a column member comprising a bent plate of channel form, the ends of the web portions of which are cut 80 away and adapted to fit against the lower surface of the upper arch bar and the upper surface of the lower arch bar, with its flanges overlapping the flanges of said arch bar and secured thereto. 85

8. A truck frame comprising an upper arch bar of channel section with its flanges projecting upwardly, a lower arch bar of channel section with its flanges projecting downwardly, an inclined member connecting the same, the webs being integrally united at their end portions, a pair of column guides, each composed of a bent plate of channel section, the ends of the web of which are cut away and are adjacent to the web portions of the arch bars, the flanges of said column guides overlapping and secured to the flanges of the arch bars. 95

9. A truck frame comprising an upper arch bar of channel section with its flanges 100 projecting upwardly, and a lower arch bar of channel section with its flanges projecting downwardly, an inclined member connecting the same, the webs being integrally united at their end portions, a pair of column guides, each composed of a bent plate of channel section, the ends of the web of which are cut away and are adjacent to the web portions of the arch bars, the flanges of said column guides overlapping and secured to the flanges of the arch bars, and bolster guides 105 secured to the said column guides. 110

10. In a truck frame of the character described; upper and lower members of channel section with integral end portions of 115 I-beam section, the lower flanges of which are turned inwardly and adapted to form journal bearing portions.

In witness whereof I hereunto affix my signature.

EDWARD C. LONG.
